(57) CLAIM

The ornamental design for an ultraviolet sanitizing recessed downlight, as shown and described.

DESCRIPTION

FIG. 1 is a front, right side and top perspective view of an ultraviolet sanitizing recessed downlight showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, left side and bottom perspective view thereof.

The broken lines in the drawing depict portions of the ultraviolet sterilizing recessed downlight that form no part of the claimed design.
